UNITED STATES PATENT OFFICE.

WILLIAM CASE, OF ST. LOUIS, MISSOURI, ASSIGNOR TO THE E. V. BENJAMIN COMPANY, INC., OF NEW ORLEANS, LOUISIANA, A CORPORATION OF LOUISIANA.

HEMMING MACHINE.

Application filed November 26, 1920. Serial No. 426,373.

To all whom it may concern:

Be it known that I, WILLIAM CASE, a citizen of the United States, and resident of St. Louis, in the State of Missouri, have invented 5 certain new and useful Improvements in a Hemming Machine, of which the following is a specification.

This invention relates to a hemming machine. Its organization comprises a machine 10 with which a single stitch is sewed through the hem of a long piece of cloth or other material at high speed. The operation of the needle is characterized by piercing the material operated on from its lower face, forming 15 a single stitch with a single loop on said lower face and a double loop on the top thereof. The operation of the needle is characterized by having imparted thereto a combined reciprocating and oscillating movement.

A continuous lubricating system is provided for some of the moving parts of the machine.

In the accompanying drawings Fig. 1 represents a front elevation partly broken away 25 of an exemplification of the hemming machine; Fig. 2 shows a section of Fig. 1 on the line 2, 2; Fig. 3 shows an enlarged front view 30 of the looper and needle of the machine in operative position at the end of the top stroke of the needle; Fig. 4 represents the elements 35 of Fig. 3 with the needle in its middle position going down; Fig. 5 shows the elements of Fig. 3 with the needle at the bottom end 40 of its stroke; Fig. 6 shows the elements of Fig. 3 with the needle in its middle position going up; Fig. 7 is a side view of the looper 45 and needle at the top end of its stroke; Fig. 8 shows a top plan view of a piece of cloth 50 with the stitch made by the machine and Fig. 9 is a bottom view of Fig. 8.

The machine comprises the base plate 20 upon which is secured the front housing 21 by means of the bolts 22 and the rear housing 45 23 by means of the bolts 24. A ball bearing race 25 is formed in the front housing 21, for the ball bearings 26. A cap 27 is secured to the front housing 21 over the race 25 by means of the screws 28. A ball bearing race 50 29 is formed in the rear housing 23 for the ball bearings 30. A cap 31 is secured to the rear housing 23 over the race 29. A main shaft 33 is journaled in the ball bearings 26 and 30. Collars 34 and 35 on the shaft 33 55 maintain it in proper lateral position. A gear

36, in this instance a Morse silent chain gear, is fastened to the shaft 33. A spur gear 37, in this instance of raw hide, is also fastened to the main shaft 33. A second Morse silent chain gear 38 is loose on the main shaft 33. 60 A friction clutch is shown to comprise the male member 40 which is loose on the shaft 33 and connected to the gear 38 and the female member 41. The latter has the annular groove 42, the counter bore 43 and is slidably 65 supported on the shaft 33. A spline 44 is interposed between the member 41 and the shaft 33. A bracket 45 extends from the rear housing 23 and has supported thereon the pivot 46. A bell crank with the single arm 70 48 and forked arm 49 is pivoted on the pivot 46. Pins 50 on the forked arm 49 engage the groove 42. A bracket 51 extends from the base 20 and has pivoted therein a foot treadle 52 by means of the pivot 53. A link 55 connects the foot treadle 52 with the arm 48 of the said bell crank. A spring 56 around the shaft 33 is located in the counter bore 43 and bears between the male member 40 and female member 41 of the friction clutch. A 80 hand operating wheel 57 is fastened to the main shaft 33. An electric motor 60 has fastened to the armature shaft a silent chain gear 61. A supporting bar 62 is fastened to the housings 21 and 23 and in turn carries the 85 journal bracket 63. A shaft 64 is journaled in the bracket 63 and has fastened thereto the chain gears 65 and 66. A frame 69 has journaled therein the axle 70 and at its upper end are guide openings 71 for cross heads 90 72 that have journaled therein the axle 73. A driving roller 74 having a sleeve of emery cloth 75 on its circumferential surface is fastened to the axle 70. A silent chain gear 76 is fastened to the axle 70. A silent chain 95 77 connects the gears 36 and 76. An idler roller 78 is fastened to the axle 73. A silent chain 79 connects the gears 38 and 66 and a silent chain 80 connects the chain gears 61 and 65. A table 81 with an opening 82 to 100 clear the needle bar, to be described, is supported in position in front of the housing 21. A chamber A comprises the roof 83, the bottom wall 84, side walls 85 and the detachable bonnet 86 and extends from the front 105 housing 21. A ball bearing race 87 is formed in the front housing 21 for the ball bearings 88. A cap 89 is secured to the said front housing 21 over the race 87. A ball bearing race 90 is formed in the rear housing 23 for 110

the ball bearings 91. A cap 92 is secured to the rear housing 23 by means of the screws 93.

An eccentric shaft 94 extends into the chamber A and is journaled in the ball bearings 88 and 91. Collars 94^a on the shaft 94 maintain it in proper lateral position. A pinion 95 is fastened to the shaft 94 and meshes with the spur gear 37. In the chamber A is located the eccentric 96 which is fastened to the eccentric shaft 94. An eccentric strap 96^a has extending therefrom the needle bar 97. A pair of counterweights 98 are fastened to the shaft 94. An oil feed 15 nipple 99 is connected with the discharge piping of an oil pump, not shown, and extends through the bonnet 86 and leads to an oil hole 100 in the shaft 94. The oil hole 100 connects with the oil hole 101 in the eccentric 96, and the latter leads to the junction between said eccentric and its strap to lubricate it. An oil outlet pipe 102 extends 20 from the bottom wall 84 of the chamber A and connects with the inlet pipe of said oil pump. By this means a continuous lubricating system is provided in the chamber A for the eccentric and its strap. A needle 103 with the eye 104 is supported in the top end of the needle bar 97 and a take up 105 having the eye 106 is fastened to the needle bar. In the roof 83 of the chamber A is supported a journal bracket 107 with the detachable cap 108. An oscillating guide 109 has formed therewith the trunnions 110 and 35 the central guide opening 111. The trunnions 110 are supported in the journal bracket 107 and the needle bar 97 extends through and is guided in the guide opening 111.

A cap 112 is supported upon the front housing 21 and is detachably connected thereto by means of the bolts 113. A ball race 114 with the ball bearings 115 is formed in the cap 112. A cap 116 is secured to the cap 112 over the race 114. A looper shaft 118 is journaled in the ball bearings 115 and has fastened to one end thereof the pinion 119 which meshes with the spur gear 37. A looper 120 with the pointer end 121 and heel 122 is detachably connected to the other end 45 of the looper shaft 118. Collars 123 and 124 are secured to the looper shaft 118. An upper guide 125 is shown with the flange 126. The latter has an opening for the shaft 118 and is clamped between the front face of the cap 112 and the collar 124. A lower guide 127 is supported upon and fastened 55 to the bracket 128 and the latter is fastened to the front face of the cap 112.

A bracket 129 has supported thereon a spool 60 130 for the thread 131 which latter leads through the eye 104 of the needle 103.

To operate the hemming machine the electric motor 60 is started and by means of the chain gears 61, 65 and the silent chain 66, rotation is transmitted to the shaft 64,

The main shaft 33 by means of the chain gears 38, 66 and the silent chain 79 receives rotation from the shaft 64, when the operator bears on the treadle 52 and engages the female member 41 with the male member 40 of the clutch. The rotations of the main shaft 33 are transmitted to the eccentric shaft 94 through the spur gear 37 and the pinion 95, whereby the needle bar 97 is oscillated and reciprocated through the oscillating guide 109. The looper shaft 118 receives rotation from the shaft 33 through the pinion 119 and spur gear 37. The cloth or other material 135 is located upon the table 81 and is folded and then directed between the guides 125 and 127 to form a hem 136 on its selvedge. The material with the hem is pulled through said guides by the coaction of the driving roller 74 and the idler roller 78 in the path of the needle 103, by which it is pierced to form a single chain stitch with a pair of loops on the top face of the hem and a single loop on the bottom face of the material, the needle entering the cloth through its bottom side.

Referring particularly to Figs. 1 and 3 to 7 it will be noted that for each revolution of the looper 120 one stitch is made in the cloth. The needle bar 97 is oscillated and reciprocated by means of the eccentric 96 and its strap 96^a, being guided at its upper portion through the opening 111 of the guide 109. In Fig. 3 the needle 103 has arrived at the end of its upward stroke having pierced the material 135 and its hem 136 and has carried the thread 131 from the previous stitch to form the lower single loop 138 on the bottom side of the material 135. The looper 120 has encircled around its body portion a loop of the thread 131 comprising the members 139 and 140. The member 139 leads from the bottom single loop 138 about to be formed and the member 140 leads from the bottom single loop 138 previously formed. The pointer end 121 of the looper 120 has just begun to form a new loop one member of which is shown at 143. The looper 120 rotates in the direction of the arrows shown in Figs. 3 to 6, and the needle 103 when it has lowered to the position of its mid stroke is shown in Fig. 4. Now a new loop with the members 143 and 144 is supported on the looper 120 and which extends through the members 139 and 140. The members 139 and 140 are about to drop from the heel 122 of the looper. In Fig. 5 the looper 120 has rotated still further and the needle 103 has arrived at the end of its down stroke. The loop having the members 139 and 140 is in position on the hem 136 constituting an element of the chain stitch. The loop with the members 143, 144 is on the looper 120. In Fig. 6 the looper 120 has made a further portion of its rotation, the members 143, 144 being still thereon. The 130

needle 103 has returned to the middle of its up stroke and is just about at a point to again pierce the material 135 to move to the position shown in Fig. 3.

5 The operations described are repeated with every revolution of the looper 120.

In Fig. 8 the chain stitch is shown with the loops having the members 139 and 140 on the top face of the hem 136, and in Fig. 10 9 on the bottom face of the material 135 are shown the single loops 138.

Having described my invention what I desire to secure by Letters Patent and claim is:

15 1. In a machine of the character described the combination of a main shaft, means to rotate the shaft, a second shaft, connections between the shafts and an oscillating and reciprocating needle bar moving with the 20 rotations of the second shaft, a needle carried by the needle bar, a pair of guides with an opening supported in the machine over the needle bar for the material operated upon, the said needle oscillating and reciprocating through the opening in said guides, 25 piercing said material and forcing a thread therethrough, forming a single loop on the bottom face of the material, a looper shaft journaled in the machine above said guides, 30 a looper having a pointer end and a heel carried by the looper shaft, the said looper engaging the thread after it has passed through the material operated upon and forming a double loop for the top face of 35 said material.

2. In a machine of the character described the combination of a pair of housings, a rotating main shaft journaled in the housings, a second shaft journaled in the housing, 40 means to rotate the second shaft from the rotations of the first shaft, a chamber formed with one of the housings, the said second shaft extending into said chamber, an eccentric fastened to the second shaft in said 45 chamber, an eccentric strap for said eccentric, a needle bar with one end carried by said eccentric strap, oscillating means to guide the upper portion of the needle bar, a needle carried by the upper end of the 50 needle bar to operate on material located

above the same and a circulating oil lubricating system connected with said chamber.

3. In a machine of the character described the combination of a rotating main shaft, a second shaft journaled in the machine, 55 connections between the shafts, a looper shaft journaled in the machine, connections between the main shaft and the looper shaft, a looper connected to the looper shaft, a chamber having a roof formed with the machine and the said second shaft extending into said chamber, an eccentric fastened to the second shaft in said chamber, an eccentric strap for said eccentric, a needle bar carried by the strap and extending through the roof 60 of the chamber, a needle carried by the needle bar, a journal bracket in the roof of the chamber, an oscillating guide having a guide opening supported in said journal bracket and guiding the upper end of the needle bar 65 and a pair of guides to guide a hem in the material operated upon above said needle bar, said guides having an opening to enable said needle to pass therethrough, said needle having an eye for a thread which is carried through said material and engaged by said looper after passing therethrough. 70

4. In a machine of the character described the combination of a rotating main shaft, a rotating eccentric shaft, a rotating looper shaft, the said eccentric shaft extending into a chamber formed with the machine, an eccentric on the eccentric shaft, a strap for the eccentric, a needle bar carried by the strap, an oscillating guide for the upper portion of the needle bar, a needle having an eye for a thread carried by the needle bar, a looper carried by the looper shaft, a guide having an opening between the looper and the upper end of the needle bar, an oil feed nipple 80 extending into the chamber and coacting with an opening extending through a portion of the eccentric shaft and said eccentric to the strap thereof and an oil outlet pipe 90 leading from said chamber. 95

Signed at Springfield in the county of Green and State of Missouri this 27 day of October A. D. 1920.

WM. CASE.
